BUILDING CONSTRUCTION

Jacque C. Morrell, Oak Park, Ill.

Application December 11, 1936, Serial No. 115,302

18 Claims. (Cl. 72—16)

This invention refers to an improved method and means of wall construction which is particularly adapted for use in buildings, such as residences, for example, wherein protection against heat and loss of heat is essential.

The invention is concerned, principally, with an improved method and means of installing and retaining wall slabs, preferably composed of material possessing good insulating qualities, in the walls of such a structure. These slabs are placed between spaced stud members in the outer walls of the structure and are affixed to the adjacent studs and thus retained in place in the wall by various alternative but nonequivalent methods and means which do not impair the good insulating characteristics of the slabs, or of the wall as a whole. Preferably the slabs are of a substantially greater thickness than the studs and are so placed in relation to the studs as to provide a substantial thickness of insulation between the inner and outer faces of the studs and the inner and outer faces of the wall.

In one specific embodiment of the invention, wherein the structural frame work of the outer walls of a building includes spaced metal studs such as, for example, H columns, I beams, or channels, having flanges substantially parallel to opposite faces of the wall, the slabs of insulating material, thicker than the studs and extending a substantial distance beyond opposite faces of the studs, are attached to the latter by members embedded in the slabs between opposite faces thereof, which members protrude from the edges of the slabs adjacent the studs and are attached to the studs by suitable hanger-clips or brackets.

Two general forms and several specific forms of the above mentioned embedded members may be employed within the scope of the invention. One of said general forms comprises a suitable bar, rod, tube, or the like which maybe embedded in the slabs at the time the latter is fabricated, or at any time prior to its placement in the wall, the embedded members being attached to the studs as the slab is placed. In the other general form, the embedded members are separable from the slabs, the latter being provided with means for inserting the embedded members therein after the slabs are placed in position in the wall.

Either of the two general types of embedded members above mentioned may either extend between and protrude from opposite vertical edges of the slab, or may extend only part way into the slab from its vertical edges, in which latter case, the end of each of said members which is

embedded in the slab may be anchored thereto in one or several manners which will be later described.

The accompanying diagram drawings, comprising Figs. 1 to 55 inclusive, illustrates several modifications of the two general forms of attaching means provided by the invention, and illustrates the use of each in a wall having spaced stud members, for attaching relatively thick slabs of insulating material to the studs.

Fig. 1 of the drawings, is an elevational view of a portion of a wall in which the attaching means for the wall slabs extend between and penetrate adjacent vertical edges of said slabs. Fig. 2 is a sectional plan view of the same wall taken along a plane indicated by line 2—2 in Fig. 1. Fig. 3 illustrates the same wall in vertical cross-section taken along a plane indicated by line 3—3 in Fig. 2. Fig. 4 is a vertical cross-section of the lower portion of the same wall taken along plane indicated by line 4—4 in Fig. 2.

Fig. 5 is a sectional plan view of a portion of the same general type of wall as shown in Figs. 1 to 4 inclusive, the section being taken through a stud and illustrating an alternative form of hanger-clip or bracket which may be employed for attaching the members embedded in the slabs to the studs. Fig. 6 is a vertical cross-section of the lower portion of the wall illustrated in Fig. 5 and is taken along the plane indicated by line 6—6 in Fig. 5.

Fig. 7 is a vertical elevation of a portion of a wall similar to that shown in Fig. 1, except that a modified form of means is employed for attaching the slabs to the studs. Fig. 8 is a plan view of Fig. 7. Fig. 9 is a fragmentary vertical cross-section of the wall taken parallel to the face of the wall through a stud, as indicated by line 9—9 in Fig. 8. Fig. 10 is a fragmentary vertical cross-section of the wall taken in a direction at right angles to that of Fig. 9, as indicated by line 10—10 in Fig. 8.

Fig. 11 is a vertical elevation of a portion of a wall having spaced stud members and superimposed slabs of insulated material extending therebetween, the slabs being attached to the studs by means of bars extending between opposite vertical edges of the slabs and embedded in recesses provided in the horizontal edges of the adjacent superimposed slabs. Portions of some of the wall slabs are cut away in this view to better illustrate the horizontal bar, stud and attaching clip. Fig. 12 is a sectional plan view of Fig. 11 taken along the horizontal plane indicated by line 12—12 in Fig. 11. Fig. 13 is a cross-

section of the wall illustrated in Figs. 11 and 12 taken along the vertical plane indicated by line 13—13 in Fig. 12. Fig. 14 is a cross-section of the lower portion of the same wall taken along another vertical plane indicated by line 14—14 in Fig. 12.

Fig. 15 is a sectional plan view of a portion of a wall similar to that of Fig. 12, except that a modified form of hanger-clip or bracket is employed for attaching the bars embedded in the slabs to the studs. Fig. 16 is a vertical cross-section of the lower portion of the same wall illustrated in Fig. 15 taken along the plane indicated by line 16—16 in Fig. 15.

15 Figs. 17, 18, and 19 are, respectively, an elevation, plan and side view of a slab of wall material adapted to extend between adjacent studs in the walls of a structure and containing embedded rods or tubular elements extending only part way 20 into the slab from opposite vertical edges thereof, with the embedded ends anchored to the slab, and with protruding end adapted to engage hanger-clips or brackets attached to the studs. Fig. 20 is a perspective view of the upper corner 25 of the slab illustrated in Figs. 17, 18 and 19 showing the profiled vertical and horizontal edges of the slab, and the protruding end of a rod embedded in the slab. Fig. 21 is a plan view of a portion of a wall, taken through a stud and illustrating how slabs such as shown in Figs. 17, 18, 30 19 and 20 may be attached to the stud. Fig. 22 is a vertical section of a portion of the wall illustrated in Fig. 21, taken along the plane indicated by line 22—22 in Fig. 21.

35 Fig. 23 is similar to Fig. 21, except that a modified form of clip or anchor is used for attaching the embedded members in the slabs to the stud.

Figs. 24, 25 and 26 are, respectively, a fragmentary elevation, partially in section, a fragmentary 40 sectional plan view and a fragmentary vertical cross-section of a slab similar to that shown in Figs. 17, 18 and 19, but employing a different method and means of anchoring the embedded members to the slab. Figs. 27 and 28 45 correspond to Figs. 24 and 25 respectively, except that another modified form of anchoring means is here shown. Figs. 29 and 30 correspond, respectively, to Figs. 25 and 26 and show another somewhat modified means of anchoring the embedded 50 rods to the slabs. Fig. 31 is a horizontal cross-section of a vertical edge portion of a slab showing another modified form of embedded member which is self-anchoring.

Fig. 32 is an elevation, partially in section, of a 55 portion of a wall employing spaced stud members, solid slabs of wall material disposed therebetween and another means of attaching the wall slabs to the studs. Fig. 33 is a cross-sectional plan view of Fig. 32 taken along a horizontal plane indicated by line 33—33 in Fig. 32. Fig. 34 is a vertical cross-section, in enlarged detail, of the means illustrated in Figs. 32 and 33 for attaching the slabs to the studs. Fig. 35 is a plan view of one end of the attaching means shown in Fig. 34. Figs. 36 and 37 are, respectively, an elevation and a cross-sectional plan view of a stud member such as shown in Figs. 32 and 33, illustrating one form of bracket or hanger-clip which may be employed in this specific embodiment of the invention. Figs. 38 and 39 correspond to Figs. 36 and 37, respectively, and illustrate another specific form of bracket or hanger-clip.

Figs. 40, 41 and 42 are, respectively, an elevation, plan view and side view of a slab of wall ma-

terial, adapted to extend between adjacent vertical studs in the walls of the structure and having members, extending part way into both its vertical and horizontal edges, which serve to attach the slab to the studs. Fig. 43 is a sectional plan view of a portion of a wall, showing how slabs such as illustrated in Figs. 40, 41 and 42 may be attached to a stud. Fig. 44 is a vertical cross-section of a portion of the same wall illustrated in Fig. 43, taken along a plane indicated by line 44—44 in Fig. 43.

Figs. 45, 46 and 47 are, respectively, an elevation (partially in section) a sectional plan view and a vertical cross-section of a portion of a wall slab and a stud member, illustrating a slab-fastening member hingedly attached to the stud and embedded in the slab along a horizontal edge of the same and anchored thereto. Fig. 47 is taken along a horizontal plane through the stud, as indicated by line 47—47 in Fig. 45.

Figs. 48, 49 and 50 are an elevation (partially in section), a sectional plan view and a cross-sectional elevation, respectively, of a somewhat different form of wall, having spaced stud members with slabs of building material deposited therebetween, the slabs being held in place by auxiliary members attached to the studs at spaced intervals and projecting into grooves provided along the edge portions of the slabs adjacent the studs. Fig. 49 represents a section of the wall taken along a horizontal plane indicated by line 49—49 in Fig. 48. Fig. 50 represents a section through the wall taken along a vertical plane indicated by line 50—50 in Fig. 49. Fig. 51 is a perspective of a portion of one of the wall slabs illustrated in Figs. 48, 49 and 50, looking toward a vertical edge of the same and more clearly illustrating the profile which occurs on opposite vertical edges of the slab.

Figs. 52, 53 and 54 illustrate, respectively, an elevation, a sectional plan view and a vertical cross-section of another wall employing spaced stud members, with slabs of building material deposited therebetween and held in place by horizontal members attached to the studs at spaced intervals. Fig. 53 represents a section taken along a horizontal plane indicated by line 53—53 in Fig. 52. Fig. 54 represents a vertical cross-section through the wall taken along a plane indicated by line 54—54 in Fig. 53.

Fig. 55 is a vertical cross-section through the wall and a portion of the floors and roof of a building and is intended to illustrate a typical form of two story construction in which the features of the invention are employed.

Referring to Figs. 1 to 4 inclusive, the spaced stud members 1 are shown as I-beams in this particular case, although H-columns, channels or the like may be employed when desired. The studs are mounted on a suitable base plate 2 which, in the case here illustrated, is embedded in the foundation 3 and the studs are surmounted by a suitable load-distributing member 4, which is shown as an I-beam in this particular case, although a channel, angle, T-bar or the like may be employed, when desired. The studs may be welded or otherwise attached in any conventional manner at their upper and lower ends to the respective plates 4 and 2.

The wall slabs 5 which, as here illustrated, are preferably substantially thicker and the studs may be substantially the same height as the stud members or, as in the case here illustrated, may be divided into a plurality of shorter superim-

posed slabs. A portion of the slab is cut away along each vertical edge, as illustrated, to allow a major portion of the slab to pass between the flanges of the adjacent studs, leaving a flanged portion 6 along one face of each vertical edge of the slab which registers against the face of the stud and locates the slab in its proper position in the wall. The opposite face of each stud is covered by auxiliary strips or blocks of insulating material, indicated in the drawings at 7 and 8, so that each stud is completely enclosed in and covered by a substantial thickness of insulating material. Insulating material in plastic form, preferably with a suitable binder, may of course, be employed when desired, instead of strips or blocks 7 and 8.

Each of the slabs 5 is provided with one or a plurality of embedded members 9 which, in this particular case, comprise tubular elements extending between opposite vertical edges of the slab. Suitable openings may be provided in the slab into which members 9 may be inserted before the slab is placed in position in the wall or members 9 may be included in the slab as it is built up, particularly in case the slab is composed of laminations of fibrous insulating material or of a moulded or cast material.

A hanger-clip or bracket 10 is attached to the flanges on the opposite faces of each stud, by welding or in any other suitable manner, not illustrated, with the face of the clip or bracket extending beyond the flanges of the stud, as shown, in such a manner that suitable projecting portions 11 disposed at the opposite ends of each member 9 engage slots 12 provided in hangers 10 and thus secure the slabs to the studs and retain the same in their proper position in the wall.

The openings in slabs 5, into which blocks 8 are fitted after the slabs are placed, are provided to allow the slabs to pass the spaced hangers 10 as they are placed between adjacent studs. The slabs are placed between the studs from one side of the wall at a slightly higher elevation than their normal position in the wall, in order that the projecting portions 11 of members 9 will not interfere with hangers 10, and after flanges 6 have been registered with the flanges of studs 1 the slab is lowered to its normal position, whereupon the protruding ends 11 of members 9 engage the slots 12 of hangers 10, locking the slabs in position.

In the particular case here illustrated, the protruding ends 11 of members 9 are separate pieces threaded into opposite ends of each tubular member in order to permit the insertion of the tubular members 9 into openings of substantially the same size provided in the slabs. However, in case members 9 are built into the slabs, the end portions 11 may be integral therewith, or, in either case, one end portion may be integral, when desired.

Also, in the particular case here illustrated, a tongue and groove construction, such as indicated at 13 in Fig. 4, or any other suitable arrangement not shown, is, preferably provided between the horizontal edges of adjacent superimposed slabs, serving to join the adjacent slabs and serving as a seal against the infiltration of air through the wall.

Obviously, in order to register the uppermost member 9 with the uppermost hanger 10, a space is left in the wall immediately beneath member 4 of the framework and above the uppermost wall slab. In the particular case here illustrated, this space, which remains after the slab is lowered to

its normal position in the wall, is filled with a suitable auxiliary strip or blocks 14, preferably of the same wall material. These strips or blocks 14 may be securely retained in position, in any desired manner and, as here illustrated, are so retained by means of suitable spikes 15 extending through openings provided in the lower flange of member 4, into the strips or blocks and, preferably, through the latter into slab 5.

The fragmentary portion of the wall shown in Figs. 1 to 4 inclusive, illustrates a portion of the outer walls of a building, such as a house, and the ends of suitable floor joists, not shown, which may be either wood, metal, concrete, or the like may be rested upon the projecting portion 16 of foundation 3 or upon a suitable plate, not illustrated, which may be attached thereto. The ceiling or second-story floor joists, not shown, may rest upon either the upper or lower flange of member 4, which, in the case of a one-story structure, may also carry conventional rafters or roof trusses, not shown. In the case of a two-story structure, the wall may be built up from the upper flange of member 4 in the same manner as the lower story wall is built up from member 2 and, of course, more than two stories may be constructed, when desired, in the same manner. A section of a typical two-story wall showing the floor and ceiling joists and the roof is shown in Fig. 55, which will be later described.

In order to cover and protect the outer face of member 4 a suitable block or strip of insulation 17 may be provided which, in the particular case here illustrated, is held in place by a flanged portion 18, disposed along the outside upper edge of the member 14.

Fig. 5 illustrates, in sectional plan view, a portion of a wall similar to that shown in Fig. 3, except that a somewhat modified form of bracket or hanger-clip 19 is employed for attaching embedded member 9 to stud 1. Fig. 6 is a vertical cross-section of the same wall shown in Fig. 5 taken along a plane indicated by line 6-6 in Fig. 5. In Figs. 5 and 6 clip or bracket 19 protrudes, as does clip or bracket 10 of Figs. 1 to 4 inclusive, beyond the flanges of the stud to which they are attached in order that bar 9 may be shorter than the distance between the flanges of adjacent studs and still engage the slots in the clips or brackets at its opposite ends. Clips 19, like clips 10, may be either welded, riveted or bolted to the studs, except that clips 19 are attached to the web of the studs instead of, as in the case of clips 10, to their flanges.

The same reference numbers are utilized in each of the Figs. 1 to 6 inclusive, to designate the same members of the assembled wall.

Figs. 7, 8 and 10 correspond, respectively, to Figs. 1, 2 and 3 and illustrate a portion of a wall similar to that of Figs. 1 to 4 inclusive, except that a different method and means is employed for attaching the slabs to the studs. Fig. 9 is a sectional elevation of a portion of the wall taken through a stud member along a vertical plane indicated by line 9-9 in Fig. 8. In the specific form of the invention illustrated in Figs. 7 to 10 inclusive, the wall slabs and studs are designated by the same reference numbers as in Figs. 1 to 6 inclusive and may be of substantially identical form, except that the fastening members attached to the studs, as well as those partially embedded in the slab, are of somewhat different form. The longitudinal partially embedded members are here designated by the reference number 20 and are each provided at their opposite

ends, which protrude from the vertical edges of the slab, with a hook 21, the upper end of which engages a hook-shaped bracket 22, or any other suitable type of hanger, not shown, which is attached to the stud. As here illustrated, rod 20 preferably is hexagonal or may be square, octagonal or of any other shape having corners or protrusions which will prevent the same from readily turning in the slab so that hooks 21 are 10 easily maintained in an upright position. Round rods or tubes may, of course, be employed, when desired, although they are not preferred with this specific form of attaching means. The slabs may be placed in position in the wall and the 15 separate members of the attaching means engaged in the same manner as above described in connection with Figs. 1 to 6.

Figs. 11, 12, 13, 14, 15 and 16 correspond, respectively, to Figs. 1, 2, 3, 4, 5 and 6 and illustrate 20 a portion of a similar wall which, instead of employing rods or tubes extending through the slab at points intermediate the horizontal edges thereof, employs rectangular bars 24 embedded in adjacent horizontal edges of superimposed slabs. 25 The reference numbers in Figs. 11 to 16 inclusive corresponding to those of Figs. 1 to 6 inclusive indicate the same elements of the wall and the description thereof is the same in both cases, except that in Figs. 11 to 16 inclusive the slabs 5, 30 instead of having the tongue and groove arrangement along their adjacent horizontal edges and instead of having rods, extending through the slabs intermediate their horizontal edges, each has a groove along each horizontal edge which 35 receives a portion of the corresponding bar 24, the opposite ends of which engage the slotted portion 12 of the clips or hangers 10 or 19, as the case may be.

Another difference between the wall illustrated 40 in Figs. 1 to 6 inclusive and that shown in Figs. 11 to 16 inclusive, is that, in the latter case, the base plate or channel 2 is inverted on the foundation 3 and the flanges of the channel engage recesses provided in the bottom edge of the lowermost slab 5, thus obviating the necessity of employing a bar 24 at this point.

In constructing the wall of Figs. 11 to 16 inclusive, the lowermost slab 5 between each pair of adjacent studs is first registered along its lower 50 edge with the flanges of channel 2 and then tipped into position between the studs with the flanges 6 along the vertical edges of the slab bearing against the adjacent faces of the studs 1. The lowermost bar 24 is then dropped into position, 55 registering with the groove provided along the upper horizontal edge of the slab and with slots 12 in the hanger-clips. The next higher slab is then registered along the groove in its bottom edge with the upper half of the lowermost bar 24 60 and, after this slab is tipped into position, the next bar 24 is dropped into place to register with the groove along the upper edge of the slab and engage the slots 12 of the hanger-clips. This is continued until the topmost slab 5 is placed. 65 The upper horizontal edge of this topmost slab is of different form than the upper edges of the lower slabs, being cut at an angle as indicated in Fig. 13, so that it will pass beneath member 4 and, preferably, having a flanged portion 18 70 which helps to retain block or strip 17 in place. The upper edge of this uppermost slab is pinned in place by means of spikes, or the like, such as indicated at 15, which pass through holes provided in the lower flange of member 4 into the 75 slab.

The slabs of wall material illustrated in Figs. 17 to 23 inclusive and there designated by reference number 25, each contain a plurality of spaced tubes or rods 26 which serve to attach the slab to hanger-clips or brackets 10, which, as 5 illustrated in Figs. 21 and 22, are attached to stud member 1. Fig. 23 illustrates the use of another type of clip or hanger 19, heretofore described. The tubes or rods 26, extend part way into the slab from its opposite vertical 10 edges and the embedded ends of members 26 are anchored to bars 27, which are embedded in the slab from its horizontal edges. In the case here illustrated, members 26 are threaded into bars 27, although they may be attached thereto in 15 any other desired manner, such as for example, by welding, rolling, swaging, or the like. The embedded members 26 and 27 may be inserted in the finished slab, or may be included in the same as it is fabricated, particularly in case the slab is 20 cast, molded, or built up of laminated thinner sheets of insulating material. Recesses 28 are provided in the two vertical edges of the slab and extend into the same for a sufficient distance beyond members 26 to accommodate clips 10 or 25 19. Thus, the protruding ends of members 26 will clear studs 1 when the slabs are placed in position in the wall, but will protrude sufficiently 30 from the adjacent edge of the slab to engage the clips or hangers. Preferably, a flange 29 is left on one face of slab 25 along each of its vertical edges. These flanges register with one face of stud members 1 and cover the same when the slabs are placed in the wall. The opposite face of each stud may be covered by separate blocks or strips 35 7 of insulating material and recesses 26 may be plugged with blocks or strips 8 of insulating material, so that the studs are entirely enclosed and protected, or, when desired, plastic insulating 40 material or the like may be substituted for either or both of the members 7 and 8. In the case 45 here illustrated, one horizontal edge of slab 25 is provided with a continuous recess or groove 30 and the opposite horizontal edge of each slab is provided with a continuous protrusion or 45 tongue 31, so that, when superimposed slabs are placed in position in the wall, the adjacent horizontal edges are interlocked in the same manner as illustrated and described in connection 50 with Figs. 1, 3, 4, and 6.

Figs. 24, 25 and 26 illustrate another method of anchoring rods 32 (which are similar to rods 26 of Figs. 17 to 23 inclusive) into slab 25. In this case rods 32 are provided with a section 33 of reduced diameter, adjacent the end of the rod which is embedded in the slab, and another embedded member 34 (which replaces member 27 of Figs. 17 to 23 inclusive) is provided with a slotted end 35, which engages portion 33 of rod 32. A shoulder 36 is provided on the extreme end of rod 32, in order to securely interlock members 32 and 34, leaving the desired portion of rod 32 protruding from the vertical edge of the slab and preventing movement thereof. Although round rods are here shown for members 32 and 34, any other desired shape may be employed.

Figs. 27 and 28 illustrate another method and means of anchoring rods 36 (which are similar to rods 26 and 32) to slabs 25. In this specific form of the invention, the hole is provided adjacent the embedded end of a rod 36, through which one end of an embedded vertical pin 37 is passed to lock the rod in place.

Figs. 29 and 30 illustrate a method and means of anchoring rods 36 in place in slab 25 which 75

is similar to that shown in Figs. 27 and 28, except that a horizontally disposed pin 38 is employed, which is similar to but preferably shorter than pin 37 and which preferably does not penetrate either face of slab 25. The hole left in one face of the slab when pin 38 is inserted is preferably filled with insulating material as indicated at 39.

Fig. 31 illustrates how a tapered and threaded member 40 may be employed in slab 23 for attaching the same to the stud members in a wall through the medium of clips or brackets, such as previously illustrated and described. Member 40, preferably has a wide-pitch thread 41, which permits its being driven into the edge of the slab and serves to anchor it in the slab. A shoulder 42 is preferably provided on the protruding end of member 40 to act as a stop, so that member 40 will not be driven too far into the slab.

When desired any of the attaching members described in connection with Figs. 17 to 31 inclusive may be employed without the anchoring means.

In Figs. 32 and 33, slabs 45 of wall material are inserted between adjacent stud members 1 and retained in place by spring-actuated bolts, or plungers 46 which engage brackets or clips 47, the latter being attached to the studs by welding or any other desired manner, not illustrated, and the bolts or plungers being housed in sheaths 49 which, in turn, are embedded in the slabs at spaced intervals along their vertical edges corresponding to the spacing of members 47. An enlarged cross-sectional detail of stud 1 and brackets or clips 47, is shown in Fig. 37, and Fig. 39 is a similar view showing a modified form of bracket or clip 48 attached to stud 1. Figs. 36 and 38 are elevational views of Figs. 37 and 39 respectively. Figs. 34 and 35 are enlarged details of plungers 46 and their complementary members. Sheath or cylinder 49 in which plunger 46 is housed, contains a suitable spring 50 which actuates the plunger and normally holds it in an extended position, except when pressure is exerted at its outer end, and a suitable stop is provided adjacent the outer end of plunger 46 and sheath 49. The stop mechanism, in this particular case, comprises a groove 51 in the outer end of plunger 46, which is engaged by a deformed end portion 52 of sheath 49. The outer end of plunger 49 is cut at an acute angle to its longitudinal axis as indicated at 53 in Fig. 35 and, as slab 45 is placed in position for insertion in the wall, the angular face of the outer end of the plunger rests against the angular face 54 of bracket 47, or the angular face 55 of bracket 48, as the case may be, and pressure exerted upon the face of the slab serves to compress spring 50 and depress the plunger allowing the slab to move into place between the studs, whereupon, when the plunger reaches slot 56 in bracket 47, or opening 57 in bracket 48, as the case may be, the spring forces it into the slot or opening and locks the slab securely in place. The preferred form of clip is illustrated in Figs. 36 and 37, since a slot such as 56 permits a slight variation in the spacing of the embedded attaching members, so that they do not require as minutely accurate spacing in relation to the clips as is the case when the opening in the clips is approximately the same size and shape as the plungers.

Although Figs. 32 and 33 illustrate the use of a plurality of superimposed slabs between each pair of adjacent studs, in much the same manner as that illustrated in Figs. 1 and 2, it is entirely within the scope of the invention to employ a

single slab between each pair of adjacent studs which may extend for example, from the base plate or foundation to or above the ceiling line of the building.

Figs. 40, 41 and 42 illustrate a slab 60 of wall material and Figs. 43 and 44 illustrate how slabs of this type may be attached to stud members 1 in a wall by means of horizontally disposed bars 61 protruding part way into the width of the slab along its horizontal edges and anchored to the slab by vertically disposed bars 62 which, in this particular case may be integral with or welded or otherwise attached to bars 61. Clips or hangers 63 are provided at spaced intervals along the stud members and members 61 register with the grooves or slots provided in clips 63 to retain the slabs in place. When slabs 60 are employed in the walls of a structure a plurality of such slabs are preferably superimposed between each pair of adjacent studs, in much the same manner as that illustrated in Fig. 11, and members 61 and 62 serve not only to attach the slabs to the studs but also interlock adjacent horizontal edges of the superimposed slabs. Grooves or recesses are provided in the horizontal edges of slabs 60 to accommodate members 61 and 62. The attaching members 61 and 62 are registered with the grooves or recesses in the upper edge of the lowermost slab and with the corresponding clips 63 after the slab is placed in position in the wall with flanges 64 bearing against the faces of the studs. The next higher slab is then placed in the wall with the recesses in its lower edge registering with members 61 and 62, previously installed. The next pair of attaching members is then inserted in the recesses in the upper edge of the slab, and so on until the wall is completed. The opposite face of each stud is preferably covered and protected by strips or blocks 65 of insulating material, as indicated in Fig. 43 or, when desired, with plastic insulating material.

Figs. 45, 46 and 47 illustrate the use of a modified form of members 61 and 62 of Figs. 40 to 44 inclusive. The modified members are designated in Figs. 45, 46 and 47 by the reference numbers 66 and 67, respectively. In this particular embodiment of the invention members 66 are hingedly attached to the flanges of studs 1, as indicated at 68, so that they may be turned back 50 against the web of the studs before slabs 60 are placed in the wall and thus will not interfere with the slab as it is placed. After slab 60 is placed with the flanged portions 64 bearing against the face of stud 1, member 66 may be lowered to 55 position in a groove provided in the horizontal edge of the slab to accommodate the same and at the same time member 67 is inserted in a recess provided in the slab, members 66 and 67 being brought into position simultaneously so 60 that the free end of member 66 engages and protrudes through slot 69 provided in the mid-portion of member 67.

In the type of wall illustrated in Figs. 48, 49 and 50, wall slabs 70, which extending between adjacent stud members 1 in the wall, are held in place by means of clips 71 which are rigidly attached to the studs at spaced intervals, by welding, bolting, riveting, or in any other conventional manner, not shown, and protrude into a 70 groove 72 (see Fig. 51) provided in the vertical edges of the slabs. Members 71, although here shown as T-bars, may be of any other desired shape such as a rectangular bar or strip or an angle, for example, having a leg or straight por- 75

tion extending into slot 72. Members 71 are preferably attached to the studs before the wall slabs are placed.

Slab 70, as shown in Fig. 51, is provided with a recess, indicated at 73, extending from the lower end of slot 72 to the bottom of the slab so that the face of the slab adjacent recess 73 may pass the protruding portion of clips 71, allowing the slabs to be placed between the studs 10 at a somewhat higher elevation than their normal position in the wall and, when the flanges 74 along the opposite face of the slab contact the adjacent face of the studs, the slab is lowered to its normal position, allowing clips 71 to enter grooves 72, thus holding the slab in its proper location in the wall.

A plurality of slabs 70 are placed in superimposed relation between adjacent studs until the space between the base plate 2 or foundation 3 and member 4 is closed except for a relatively small space immediately beneath member 4. A slab 75 of wall material is then inserted in this space and may be held in place by spikes or the like, such as indicated at 15, which are driven 25 into slabs 75 through holes provided at spaced intervals along the lower flange or member 4.

Suitable blocks or strips 17 of wall material may be provided to cover member 14 on the outer facing of the wall and these strips or blocks 17 are held in place at the bottom, in the case here illustrated, by a flanged portion 76 along the upper edge of slabs 75 and are held in place at the top by spikes 15 or the like, driven into the strips or blocks 17 through holes provided at 35 spaced intervals along the upper flange of member 4.

The faces of the studs opposite those covered by flanged portion 14 of slabs 70 are preferably covered by strips or blocks 17 of wall material and 40 recesses 73 in the slabs may be filled with strips or blocks 8. As in the wall structures previously described, plastic material or the like may be substituted for either or both of the strips or blocks 7 and 8.

45 In the wall illustrated in Figs. 52, 53 and 54, a plurality of superimposed slabs 80 of wall material extend between adjacent studs 1 and are held in place by members 81 and 82 and by the interlocking arrangement provided between the 50 adjoining slabs.

Members 81 are here illustrated as rectangular bars, although any other suitable shape, such as an angle or a Z-bar may be employed, when desired, and preferably these members extend between and are attached to the webs of adjacent studs 1 by welding or in any other desired manner, before the wall slabs are placed.

The top and bottom edges of slabs 80 are profiled, as indicated in Fig. 54 in such a manner 60 that the groove 83 provided along the lower edge of each slab may be brought into engagement with the corresponding member 81 and the top of the slab then tipped into position with the flanged portions 84 along its vertical edges bearing 65 against the adjacent faces of the studs (see Fig. 53). Member 82 is then welded, bolted or otherwise attached in any desired manner to the face of the studs to assist in holding the slab in position and strips or blocks 85 of insulating material, 70 or suitable insulating material in plastic form is installed to cover member 82, following which the next highest slab 80 may be placed in position in the wall in the same manner.

The outline of slab 80, shown in dotted lines in 75 Fig. 54, illustrates the position of the slab as

groove 83 is about to be registered with member 81. It will be noted that groove 73 is so shaped that, while the slab is retained in the position indicated by the dotted lines in Fig. 54, it may be lowered sufficiently to allow the top of the slab to clear bar 81, the shape of slot 83 then allowing the slab to be tipped into its normal position in the wall.

Auxiliary blocks or strips 7 of wall material may be applied to the face of the studs opposite the flanged edges 84 of the wall slabs or, as previously mentioned in connection with other figures of the drawings, plastic insulating material or the like may be substituted for the strips or blocks 7.

The uppermost bar 81 is spaced a short distance beneath member 4, which surmounts the studs and distributes the superimposed roof and floor load thereto, leaving a space between the top of uppermost slab 80 and the bottom flange of member 4. This space, in the particular case here illustrated, is filled between adjacent studs by two slabs 86 and 87 of wall material which are held in place by spikes or the like indicated at 15, the spikes being driven through holes provided in the lower flange of member 4 into the slabs.

With further reference to the relation of adjacent slabs to each other and to the retaining means therefor, it will be noted that, although the recesses provided along the lower edge of these slabs for receiving bars 81 are preferably somewhat larger than the bars, one face of the recess preferably rests snugly against one face of bar 81, preventing movement of the lower end of the slab in one direction. The lower end of the slab is prevented from moving in the opposite direction by its angular bearing along line 88 with the top of the adjacent slab, the latter being, in turn, prevented from movement in this direction by bar 82 and, in the opposite direction, by its angular line of bearing, as indicated at 88, with the lower edge of the next higher slab. Thus the slabs 80 are firmly held in place along both their top and bottom edges by bars 81 and 82 and by the interlocking arrangement provided between adjacent slabs.

Except for the specific form of wall slabs employed and their method and means of installation and attachment to the studs, as above outlined, the wall illustrated in Figs. 52, 53 and 54 may be constructed in substantially the same way as illustrated and described in connection with the other figures of the drawings, and is so illustrated. The reference numbers in Figs. 52, 53 and 54, which correspond to the reference numbers employed in the other figures of the drawings, refer to the same elements of wall.

Fig. 55, as previously mentioned, illustrates a cross-section through the side-wall, floors, ceiling and roof of a portion of a typical two-story structure, employing features of the invention. This 60 structure employs a conventional poured concrete foundation, the upper portion of one wall of which is indicated at 3. A base plate 2 is provided in the foundation for the outer walls of the structure and in this particular case, comprises a 65 channel with its flanges embedded in the concrete foundation and which is also preferably retained by anchor-bolts or the like, not illustrated. A flat plate, channel, I or H beam, or the like may, of course, be substituted by channel 2, when 70 desired.

Wood joists are illustrated in this particular embodiment of the invention, although metal or concrete joists or the like of any desired form may be employed, when desired. The first floor 75

joists 90 may rest upon foundation 3 or, preferably, as here illustrated, upon a suitable wood plate 91, which may be anchored to the foundation in any well known manner, not illustrated, and a header 92 may also be provided for joists 90, when desired. A sub-floor 93 and a finished floor 92 of conventional form are here shown, although any desired type and form of floor materials may be employed.

10 The construction of the second floor may be substantially the same as that of the first, except that the ends of joists 95 rest upon a flange of member 4, which in turn, is supported by and distributes the superimposed load to the spaced 15 first floor stud members 1. A sub-floor 93' and a finished floor 94' are also provided over the second floor joists 95, and, in the case here illustrated, the first floor ceiling, which is supported by joists 95, comprises sheets 96 of rigid insulated material, or the like, nailed to the joists in any conventional manner, not illustrated. Plaster, indicated at 97, may be applied to the 20 under surface of sheets 96 to finish the ceiling.

Spaced stud members 1' for the outer walls of 25 the second-story are mounted upon the upper flange of member 4 and surmounted by a horizontal member 98, which in this particular case, is illustrated as a T-bar, one flange of which receives the second-story ceiling joists 99. The 30 second-story ceiling may be finished in the same manner as the first-story ceiling, as indicated at 96' and 97'.

Rafters 100, in the particular case here illustrated, are notched adjacent their lower ends as 35 indicated at 101 and thereby supported on joists 99 to which they may be nailed in any conventional manner. Suitable sheathing 102 and shingles 103 of any conventional form are attached to rafters 100 in the usual manner.

40 The portions of the structure so far described are conventional and are intended to illustrate how conventional roof, floor and ceiling construction may be employed in conjunction with the features of the invention, which is particularly concerned with the outer walls of the structure. It is, of course, to be understood that any other conventional, as well as special types of roof, floor 45 and ceiling construction may be employed in conjunction with the features of the invention and such departures from the construction here illustrated are entirely within the scope of the invention.

Stud members 1 and 1', in the particular case here illustrated, are preferably of metal and may 55 comprise standard or special I beams, H columns, channels, T-bars, angles or the like, or special drawn, stamped or formed metal shapes of any desired type, may be employed. Wood studs may be employed, when desired, but, in such cases, 60 wood beams are preferably substituted for the metal members 2, 4 and 98.

The metal studs may be welded at their top and bottom ends to members 2, 4 and 98, or may be attached thereto by bolting, riveting, or any other conventional manner.

65 The wall slabs 25 indicated in Figs. 17 to 20 inclusive, of the drawings, have been shown in Fig. 55 to illustrate the adaption of the features of the invention to this particular form of structure, but, it will, of course, be understood that any of the other specific form of wall slabs disclosed herein and any of the methods for attaching the same to the stud members are equally adaptable. The description of wall slabs 25 of 70 Fig. 55 and the manner and means whereby they

are attached to the studs, is the same as that of Figs. 17 to 20 inclusive, above described, and the reference numbers in Fig. 55 corresponding to those of Figs. 17 to 20 inclusive, indicating the same members of the outer wall structure.

75 Relatively narrow auxiliary slabs, blocks, or strips 104 and 105 are provided to fill the space left between the top of slabs 25 and member 4 and 98, respectively, these auxiliary members being held in place by spikes or the like 15, which 10 are inserted into members 104 and 105 through holes provided at spaced intervals along the flanges of members 4 and 98, respectively.

Although wood-siding is indicated at 106, in Fig. 55, the invention contemplates the use of any 15 desired type of exterior finish for the wall slabs, such as, for example, brick or stone veneer, stucco, metal siding, or the like. Exterior finishes, such as plywood, or sheets of any other desired material which is sufficiently resistant to deterioration 20 from moisture and varying weather conditions, may be applied to the slabs after they are installed or may be furnished integral with the individual wall slabs, being attached, in the latter case, to the underlying surface of the slabs 25 by glueing, or in any other desired manner.

A plaster finish 107, applied directly to the interior surface of the wall slabs, is here illustrated, although the invention contemplates the use of any other accepted type of interior finish, 30 such as for example, wood or plywood panels, metal sheets, tiling or simulated tile, linoleum, or the like, which may be integral with the slabs as they are installed, or may be attached thereto in any desired manner after the slabs are 35 installed in the wall. Reinforced mesh, such as expanded metal lath, or the like, may be employed with plaster or other plastic finishes on the interior surface of the wall, when desired, as well as with the stucco finishes, or the like, for the 40 exterior surface.

It will be apparent from the foregoing that the invention provides a number of related but non-equivalent methods and means of attaching relatively thick slabs of wall materials to spaced stud 45 members in the walls of a structure. Each of these methods and means is particularly well adapted to use with wall slabs composed primarily of the so-called "rigid" type of heat-insulating materials such as gypsum blocks, slabs of insulation composed of fibrous materials, of vegetable, animal or mineral origin, as well as other types of insulating slabs or blocks such as, for example, cast or molded materials containing ingredients 50 of good insulating quality or a high percentage 55 of relatively small voids or pockets of entrapped air or inert gas. The features of the invention are particularly desirable in connection with the use of slabs or blocks of insulating materials since 60 the methods and means of attachment provided do not materially decrease the overall efficiency 65 of the insulating material used and eliminate penetrating members of high heat conductivity.

70 However, the invention is not limited to the use of materials of good heat insulating quality for the wall slabs, since the methods and means herein provided for attaching the slabs to spaced stud members will also prove advantageous for attaching other types of wall materials, particularly in certain types of buildings where a high degree of insulating efficiency is not essential. Molded or precast slabs of hydraulic cement, concrete, natural or synthetic resins, ceramic materials and the like may be attached to the fram- 75

ing members of any type of structure in the manner and by the means herein provided.

As applied to buildings such as houses, office buildings, factories and the like, any desired form and type of interior and exterior wall materials may be utilized in conjunction with the wall slabs. When plaster is employed as an interior finish it is preferably applied directly to the interior surface of the slabs although expanded metal 10 lath, wire mesh or the like may, of course, be utilized as a base, when desired. Stucco and kellastone or the like may be applied to the exterior surface of the slabs either without or, preferably, with a suitable reinforcing mesh. Brick 15 or stone veneer may be applied over the slabs and wood or metal siding of any desired type as well as wood or composition shingles may be employed as an external finish. When wood siding, shingles or panels of wood, metal or composite materials are employed suitable nailing strips may be anchored to the slabs in any desired manner such as, for example, by embedding or anchoring bolts, metal clips or the like in the insulating material and attaching the same to the nailing strips. 20 25 Masonry veneer may also be anchored to the slabs in a similar manner.

It will also be understood that, although metal studs such as I beams or H columns are shown in the illustrations, wood framing may be employed 30 with equal facility, in which case the wood studs may be of either square, rectangular, I or H shape in cross-section, with the clips or brackets for attaching the slabs either nailed or bolted thereto.

It will, of course, be understood that various 35 combinations of the features of the invention, other than the combinations illustrated and described, will be obvious to those skilled in the art and are therefore entirely within the scope of the invention, as defined by the appended claims. 40 The same applies to various modifications and minor departures from the specific forms of wall slabs as well as the method and means of attaching the wall slabs, herein illustrated and described.

45 I claim as my invention:

1. A wall comprising, in combination, spaced stud members, slabs of wall material extending between adjacent studs, auxiliary members embedded in the slabs at spaced intervals, said auxiliary members protruding only from edges of the 50 slabs and being adapted to pass between the inner edges of adjacent studs, and means for attaching the protruding portions of said auxiliary members to the studs, whereby to maintain the slabs in 55 position in the wall, one face of said slabs substantially completely covering said stud members.

2. A wall comprising, in combination, spaced stud members, slabs of insulating material extending between adjacent studs, attaching means 60 for the slabs disposed on said studs at spaced intervals, auxiliary relatively slender members partially embedded in said slabs at spaced intervals and adapted to pass between the inner edges of adjacent studs and means for engaging portions 65 of said auxiliary members which protrude from the slabs with said attaching means on the studs, whereby to attach the slabs to the studs, said wall being further characterized in that the studs, attaching means and auxiliary members are covered on a face of the wall by a substantial thickness of insulation.

3. A wall comprising, in combination, spaced stud members, a plurality of superimposed slabs of wall material extending between adjacent 75 studs, auxiliary members engaging recesses pro-

vided along the abutting horizontal edges of adjoining slabs, a portion of said auxiliary members protruding from opposite vertical edges of said adjoining slabs, attaching means for the slabs attached to said studs and provided with openings, and means for entering said protruding ends of the auxiliary member into said openings in the attaching means, whereby to attach the slabs to the studs. 5

4. A wall comprising, in combination, spaced 10 stud members, a slab of insulating material extending between adjacent studs, brackets attached to said studs and provided with openings, relatively slender auxiliary members extending only part way into the slab at spaced intervals 15 along the vertical edges thereof adjacent the studs, end portions of said auxiliary members protruding from said vertical edges of the slab and means for registering the protruding ends of said auxiliary members with the openings in said 20 brackets, whereby to attach the slab to the studs.

5. A wall comprising in combination, spaced 25 stud members, a slab of insulating material extending between adjacent studs, suspending means attached to said studs at spaced intervals, relatively slender auxiliary members extending only part way into the slabs at spaced intermediate points along the vertical edges thereof adjacent the studs, end portions of said auxiliary members protruding from said vertical edges, 30 hooks attached to said protruding ends of the auxiliary members and means for engaging said hooks with said suspending means, whereby to attach the slab to the studs.

6. A wall comprising, in combination, spaced 35 stud members, a plurality of superimposed slabs of wall material extending between adjacent studs, the abutting horizontal edges of adjoining slabs being provided with corresponding recesses, bars extending only part way into the slab from 40 opposite vertical edges thereof, said bars being disposed in said recesses and one end of each of said bars protruding from the corresponding vertical edges of the slabs, and means for attaching the protruding ends of said bars to the studs, 45 whereby to attach the slabs to the studs.

7. A wall comprising, in combination, spaced 50 stud members, a plurality of slabs of insulating material disposed in superimposed relation between adjacent studs, auxiliary members attached to the studs and protruding from the edges of the latter adjacent the slabs at spaced intervals, recesses in one face of each slab along its edges adjacent the studs, said recesses permitting the slabs to be placed in position between 55 the studs and grooves in the slabs along the vertical edges thereof adjacent the studs adapted to receive the protruding portions of said auxiliary members, whereby to attach the slabs to the studs. 60

8. A wall comprising, in combination, spaced 65 vertical stud members, spaced horizontal members extending between adjacent studs and attached thereto, slabs of insulating material adapted to be placed between adjacent studs, said slabs being provided with a groove along one horizontal edge of each adapted to receive said spaced horizontal members, and separate horizontal members attached to the studs and bearing 70 against the slabs adjacent the opposite horizontal edges thereof, the contour of said slabs and the location of said horizontal members being such as to retain the slabs in position in the wall. 75

9. A wall comprising, in combination, spaced vertical stud members, spaced horizontal members extending between adjacent studs and automatically attached thereto, slabs of insulating material adapted to be placed between adjacent studs, said slabs being provided with a groove along one horizontal edge of each adapted to receive said spaced horizontal members, and separate horizontal members attached to the 5 studs and bearing against the slabs adjacent the opposite horizontal edges thereof, the contour of said slabs and the location of said horizontal members being such as to retain the slabs in position in the wall.
10. A wall comprising, in combination, spaced stud members, slabs of wall material extending between adjacent studs, said slabs being of greater width and length than thickness and having a front face and rear face, the width of said 10 slabs across said front face being greater than the distance between the inner edges of adjacent studs, attaching means for said slabs disposed on said studs at spaced intervals, auxiliary members embedded in said slabs at spaced intervals, 15 portions of said auxiliary members protruding from said slabs a distance short of the edges of said front face, and means for engaging portions of said protruding members with said attaching means on the studs whereby to attach said slabs 20 to said studs.
11. A wall comprising, in combination, spaced stud members, slabs of wall material extending between adjacent studs, said slabs being of greater width and length than thickness and having 25 a front face and rear face, the width of said slabs across said front face being greater than the distance between the inner edges of adjacent studs, attaching means of said slabs disposed on said studs at spaced intervals, auxiliary 30 members extending through the slabs and disposed at spaced intervals intermediate the top and bottom edges of the slabs, portions of said auxiliary members protruding from said slabs a distance short of the edges of said front face, and means for engaging portions of said protruding members with said attaching means on the studs whereby to attach said slabs to said 35 studs.
12. A wall comprising, in combination, spaced stud members, slabs of wall material extending between adjacent studs, said slabs being of greater width and length than thickness and having a front face and rear face, the width of said slabs across said front face being greater than the distance between the inner edges of adjacent 40 studs, suspending means for the slabs attached to said studs at spaced intervals and provided with openings adapted to receive separate suspending means embedded in said slabs, said suspending means in the slabs comprising relatively slender auxiliary members disposed at spaced intermediate points in opposite vertical ends of the slabs and having portions protruding from said ends of said slabs a distance short of the edges of said front face, said protruding portions extending into said openings in the suspending means on the studs, whereby to retain the slabs in place in said wall.
13. A wall comprising, in combination, spaced stud members, slabs of wall material extending between adjacent studs, said slabs being of greater width and length than thickness and having a front face and rear face, the width of 45 said slabs across said front face being greater than the distance between the inner edges of adjacent studs, attaching means for the slabs attached to the studs at spaced intervals and provided with slots, relatively slender auxiliary members extending into the slabs and protruding therefrom a distance short of the edges of said front face at spaced intermediate points along its vertical edges, said auxiliary members being adapted to pass between 50 the vertical edges of adjacent studs and means for suspending the protruding portions of said auxiliary members in the slots of said brackets, whereby to attach the slab to the studs.
14. A wall comprising, in combination, spaced stud members, slabs of wall material extending between adjacent studs, said slabs being of greater width and length than thickness and having a front face and rear face, the width of said slabs across said front face being greater than the distance between the inner edges of adjacent 55 studs, brackets attached to the studs at spaced intervals and provided with slots, relatively slender auxiliary members extending into the slabs and protruding therefrom a distance short of the edges of said front face at spaced intermediate points along its vertical edges, said auxiliary members being adapted to pass between the vertical edges of adjacent studs and means for suspending the protruding portions of said auxiliary members in the slots of said brackets, whereby to attach the slab to the studs.
15. A wall comprising, in combination, spaced stud members, a slab of insulating material extending between adjacent studs, sheaths embedded in the slab at spaced intervals along the edges of the slab adjacent the studs, movable plungers in said sheaths, a spring urging each of said plungers from its sheath and from the adjacent edge portion of the slab, means permitting only an end portion of each plunger to protrude from the sheath and from the adjacent edge portion of the slab, and means for engaging the protruding end of each plunger with the adjacent stud, whereby to attach the slab to the studs, said plunger engaging means comprising spaced clips attached to the studs, said clips being provided with elongated openings extending parallel to the vertical axis of the stud and adapted to receive said plungers.
16. A wall comprising, in combination, spaced stud members, slabs of wall material extending between adjacent studs, said slabs being of greater width and length than thickness and having a front face and rear face, the width of said slabs across said front face being greater than the distance between the inner edges of adjacent 60 studs, a groove in the slab along each vertical edge thereof adjacent the studs, and auxiliary members for attaching the slab to the studs, said auxiliary members being rigidly attached to the studs and extending past the vertical edges thereof into said recesses in the slab.
17. A wall comprising, in combination, spaced stud members, slabs of wall material extending between adjacent studs, said slabs being of greater width and length than thickness and having a front face and rear face, the width of said slabs across said front face being greater than the distance between the inner edges of adjacent 65 studs, supports attached to the studs at spaced intervals and provided with slots, relatively slender auxiliary members extending into the slabs and protruding therefrom a distance short of the edges of said front face at spaced intermediate points along its vertical edges, said auxiliary members being adapted to pass between 70 the vertical edges of adjacent studs.
- 75

the vertical edges of adjacent studs and means for suspending the protruding portions of said auxiliary members in the slots of said supports, whereby to attach the slab to the studs.

5 18. A wall comprising, in combination, spaced stud members, slabs of wall material extending between adjacent studs, said slabs being of greater width and length than thickness, supports attached to the studs at spaced intervals

and provided with slots, relatively slender auxiliary members extending into the slabs and protruding therefrom, said auxiliary members being adapted to pass between the vertical edges of adjacent studs, and means for suspending the protruding portions of said auxiliary members in the slots of said supports whereby to attach the slab to the studs.

JACQUE C. MORRELL.
